UNITED STATES PATENT OFFICE.

CHARLES S. PALMER AND DEAN PALMER, OF SARANAC LAKE, NEW YORK.

PAPER-PENCIL SHARPENER.

1,234,686.

Specification of Letters Patent. Patented July 24, 1917.

Application filed October 27, 1916. Serial No. 128,113.

To all whom it may concern:

Be it known that we, CHARLES S. PALMER and DEAN PALMER, citizens of the United States, residing at Saranac Lake, in the 5 counties of Essex and Franklin, respectively, and State of New York, have invented a certain new and useful Improvement in Paper-Pencil Sharpeners, of which the following is a specification, reference being had therein 10 to the accompanying drawings.

Our invention relates to attachments for lead pencils and has for its object an improved holder or clip which is particularly designed to be used in connection with paper 15 rolled lead pencils and to act both as a holder and sharpener for the same. The device consists of a spring metal holder which is adapted to fit about a lead pencil and which is provided with a clip for holding the 20 pencil in the pocket of the user and with means for cutting and sharpening the pencil all as hereinafter set forth.

Our invention will be fully understood from the following description taken in connection with the accompanying drawings and the novel features thereof are pointed out and clearly defined in the claims at the close 25 of this specification.

In the drawings, Figure 1 is an elevation 30 of a paper rolled lead pencil provided with a device embodying the invention.

Fig. 2 is an enlarged detail in perspective of a device embodying the invention.

Fig. 3 is a top plan view of the device 35 shown in Fig. 2.

Fig. 4 is an enlarged view in perspective of a modified form of device embodying the invention.

Having reference to the drawings there is 40 shown at 11 a pencil of the usual paper rolled type which consists of a spiral strip of paper wound in the ordinary manner. At 12 is shown a holder consisting of a split band of spring metal which is adapted to be 45 slipped over the pencil 11 and make a snug fit therewith as shown in Fig. 1. The band 12 has at one side a depending tongue or clip 13 which is also of spring metal and is preferably substantially of the shape shown. 50 The tongue 13 is arranged to engage the outer wall of the pocket of the user when the pencil is inserted in the pocket in a manner well known to those skilled in the art.

One end of the split metal band 12 has an

in-turned portion 14 which is sharpened at 55 its inner edge to form a knife edge by which a strip of the pencil 11 may be readily severed when desired by applying a slight pressure at the end of the clip. In order that the knife edge 14 will not sever the strip of 60 paper of which the pencil consists or unduly injure the pencil when the device is being used as a holder the band 12 is turned outwardly at 15 as shown in Fig. 3 so that the sharpened edge of the in-turned portion 14 65 does not press against the pencil unless pressure is applied. The width of the band 12 is preferably greater than the width of the paper strip of which the pencil consists so that sufficient strength may be obtained to 70 provide a strong serviceable device. In order that the cutter may not sever more than one strip at a time, the clip is beveled as shown at 16 to render the cutting portion 14 of slightly greater width than the strip of 75 which the ordinary paper pencil consists. In this manner a cutter of the proper size is provided.

The device is further provided with means for sharpening the lead of the pencil which 80 consists, in the preferred form, of a V-shaped slot 17 located in the upper surface of the metallic band 12 above the juncture of the band with the tongue 13. The edges 18 and 19 of the V-shaped opening 17 are 85 sharpened and may be used to sharpen the lead of the pencil.

In Fig. 4 is shown a modified form of holder which is similar to the holder described with the exception that the V- 90 shaped slot referred to above is omitted and a triangular shaped opening 21 is provided in the end of the metallic band 12 opposite to that at which the sharpened portion 14 is located. The triangular shaped opening 21 95 is provided with two sharpened sides 22, 23 by which the lead may be sharpened when desired.

The clip ordinarily is secured to a pencil in a manner to be used as a holder as shown 100 in Fig. 1. When it is desired to sharpen the pencil it is simply necessary to slip the clip along the pencil until the blade 14 is adjacent the lowermost strip of paper. A slight pressure above the in-turned end of the band 105 12 causes it to spring inwardly so that the knife edge will pass through and sever the strip in question. The device may then be

removed over the end of the pencil and after the severed strip has been unrolled the lead may be sharpened in the manner described.

What we claim is:

- 5 1. The improved pencil attachment comprising a split band of spring metal, one of the ends formed by the split being abruptly turned in toward the center of the band and provided with a knife edge which is substantially parallel with the line of the split.
- 10 2. The improved pencil attachment comprising a split band of spring metal having a depending portion forming a pocket engaging clip, one end of the band being abruptly turned in toward the center of the band and sharpened at the inward end.
- 15 3. The improved pencil attachment comprising a split band of spring metal having a depending portion forming a pocket

engaging clip, one of the open ends of the band being bent outwardly and then abruptly inwardly toward the center of the band and being sharpened at its inward end.

4. The improved pencil attachment comprising a split band of spring metal having a depending portion forming a pocket engaging clip, and having an opening with sharpened edges, a portion of the band being turned inwardly abruptly toward the center of the band and having a sharpened edge.

In testimony whereof we affix our signatures, in presence of two witnesses.

CHARLES S. PALMER.
DEAN PALMER.
